UNITED STATES PATENT OFFICE.

CHARLES S. BUSHNELL, OF ROCHESTER, NEW YORK, ASSIGNOR TO GENERAL RAILWAY SIGNAL COMPANY, OF ROCHESTER, NEW YORK.

INTERMITTENT-INDUCTIVE TRAIN CONTROL.

Application filed April 8, 1925. Serial No. 21,554.

This invention relates to automatic train control systems of the intermittent inductive type.

In certain well known systems of intermittent inductive train control, control influences are transmitted from the trackway to a moving vehicle by diverting flux emanating from a flux producing coil carried by the car to a secondary or influence receiving coil disposed adjacent to such flux producing coil when the car element including these coils passes by a trackway device comprising an inert or unmagnetized magnetic body. In practice this magnetic body has a bucking coil associated therewith, and is active and able to divert flux to the secondary coil only if this bucking coil is open-circuited and is ineffective and inactive when this coil is closed in a circuit of low resistance; such diversion of flux inducing a voltage in the secondary coil in proportion to the rate at which the flux is diverted. In practice, it has been found that an influence communicating arrangement of this kind is very desirable for transmitting control influence through an intervening air gap inductively, for the reason that it induces current in the receiving coil the strength of which depends on the speed of the train; so that a much stronger impulse is transmitted at the higher speeds, which is found advantageous in that the time during which the current may act decreases as the speed of the train increases; so that, the net result is the transmission of an effective control influence at all speeds above a certain low speed value which in practice has been found to be about 3 miles per hour. In previous proposed systems of the kind mentioned, it was impossible to transmit a control influence below 3 miles per hour for the reason that the electro-responsive device which is intended to respond to the control influence transmitted in this way, could not be adjusted to its most critical value, for if this were done it would respond when the car-carried equipment moved by a trackway device in its inactive or short-circuited condition, because a certain limited inductive effect is produced by a trackway device even if its coil is closed circuited, especially at those speeds at which the influence communicating means functions the best. In accordance with the present invention it is proposed to change the sensitiveness of the

car-carried influence receiving means at different speeds, so that control influences may be transmitted at speeds less than 3 miles per hour; and as a further object and purpose it is proposed to simulate movement of the train by varying the current in the flux producing coil, so that a change of flux in the secondary coil takes place by reason of variation of the flux producing current at a time when the car-carried apparatus is in inductive communication with an active trackway device. Other objects, purposes and characteristic features of the invention will appear as the description thereof progresses.

In describing the invention in detail, reference will be made to the accompanying drawings in which:

Fig. 1 illustrates a simple type of block signaling system upon which the trackway apparatus of a train control system embodying the present invention is superimposed;

Fig. 2 shows inductive influence communicating means of the type above mentioned in which the current of the primary or flux producing coil is increased when the speed of the train is below a certain value;

Fig. 3 shows a similar system to that shown in Fig. 1 in which the potential applied to the detecting or control relay is reduced when the train travels at less than a certain speed;

Fig. 4 shows a system of influence communicating means similar to that shown in Figs. 1 and 2, in which the unidirectional flux producing current is pulsated at speeds below a certain value; and

Fig. 5 shows a system similar to that shown in Fig. 3 in which the primary unidirectional current is pulsated at the rate of movement of the train at all speeds of the train, the rate of interruption or pulsation of the current being such that this current is practically constant at the higher train speeds.

Trackway apparatus.—The trackway apparatus adaptable for use with the car-carried apparatus illustrated has been shown in Fig. 1, and consists of a simple type of block signal system upon which suitable influence transmitting trackway devices are superimposed, together with means for controlling the same.

Referring to Fig. 1 the track rails 1 are divided by insulating joints 2 into blocks

in the usual manner, the block I and the adjacent ends of two other blocks H and J having been shown. Since the various blocks are the same, like parts of each block are designated by like reference characters having distinctive exponents. At the entrance end of the block I is provided a track relay 3, which under normal clear traffic conditions of this block is energized by current flowing through the track rails of this block and derived from a track battery 4 at the exit end of the block, the normal direction of traffic being as indicated by the arrow, this circuit thus constituting the usual closed track circuit. Near the entrance end of the block is provided a line relay 5 which under normal clear traffic conditions of the block I and the block J next in advance is energized through a circuit including the front contact 6 of the track relay 3 and the front contact 7¹ of the track relay 3¹.

Although the influence communicating means embodying the present invention may be applied to train control systems in which cab signals are used and in which wayside signals are not absolutely necessary, it may be used in connection with wayside signals of either the color light or semaphore type, and semaphore signals Z only have for convenience been shown conventionally without illustrating their well known operating mechanism or control circuits. The apparatus thus far described is that used in practically every modern block signal system.

In addition to this apparatus there is provided at the entrance to the block I a track element T comprising a U-shaped core 9 preferably constructed of laminated magnetic material terminating in enlarged pole pieces 10 and having a coil 11 thereon which is normally closed in a circuit of low resistance through the front contact 12 of the line relay 5. This track element T is preferably located a distance in the rear of the entrance end of the block I, so that it is encountered by a suitable car-carried device of a train before the first axle of the train enters this block, this to avoid the train stopping itself, so to speak, by dropping the track relay of this block and placing the device T in its active condition before the car element has passed the same.

It is believed unnecessary to consider in detail the movements of trains in the various blocks, it being obvious from the drawings that the track element T has its coil 11 closed in a circuit of low resistance, and is therefore inactive, when the block I at the entrance to which it is placed and the block J next in advance of this block are unoccupied, and that it has its coil open-circuited when either of these blocks are occupied; so that, this trackway device T is inactive under clear traffic conditions ahead and is active under both caution and danger traffic con-

ditions ahead. This control for the trackway device T should be borne in mind in connection with the description of the operation of the various types of car-carried apparatus described hereinafter.

Car-carried apparatus.—Since the present invention relates particularly to influence communicating means for train control systems, it is considered unnecessary to show specific means for limiting the speed of the train or for effecting a brake application regardless of speed, and in order to show a simple device actually capable of controlling a train an electro-responsive device EPV has been illustrated which may be assumed to be a device for effecting an automatic brake application, either by controlling a suitable brake pipe venting device or a brake valve actuator or for initiating a suitable speed restricting mechanism. This device EPV is preferably so constructed that it may be energized by pulsating current; that is, a direct current having a ripple thereon.

In the arrangement shown in Fig. 2 the car element L comprises a core 15 of inverted U-shape preferably constructed of laminated magnetic material and terminating in downwardly facing pole pieces 16. The leading leg of this core 15 has a primary coil P contained thereon and the trailing leg is provided with a secondary coil S. The car-carried apparatus also includes a control relay CR which preferably comprises an electro-responsive device which has its moving parts well balanced and pivotally mounted about a vertical axis so that it is substantially immune to the jars and vibrations ordinarily encountered upon a railway vehicle. In order to change the characteristics of the car-carried apparatus in accordance with speed, as heretofore mentioned, a suitable speed responsive device is preferably provided. In the arrangement shown this speed responsive device G is one of the well known centrifugal type and comprises a shaft 17 driven from the wheels of the vehicle in any suitable manner, on which is contained a grooved collar 19. An insulated contact arm 23 pivotally supported at 24 has a bifurcated end 25 engaging the grooved collar 19. It is of course obvious from the drawings that the arm 23 responds to the speed of the vehicle at all times.

The primary coil P of the car-carried element L is normally energized by direct current through the following circuit:—beginning at the terminal B of a suitable source of energy (not shown) such as a battery, the other terminal of which is connected to a common return wire C, wire 28, front contact 29 of the control relay CR, wire 30 normally closed contact 31 of the push button 32, wire 33, rheostat 34, contact arm 23 of the governor G, wire 35, winding of the device EPV, wire 36, primary coil P, wire 37,

back to common return wire C. The various parts and voltages are so proportioned that a comparatively heavy current flows in the primary coil P thereby producing a large magneto-motive-force in this car element tending to send a flux through the core 15 thereof. The secondary coil S is connected in series with the control relay CR through the following circuit:—beginning at the 10 terminal B of the control relay CR, wire 38, front contact 39 of the control relay CR, wires 40 and 41, winding of the control relay CR, wire 42, secondary coil S, wire 43, back to common return wire C. The winding of 15 the control relay CR and that of the secondary coil S are so proportioned and have such a resistance that the current flowing in this circuit is of a value to maintain this relay energized to a suitable margin above 20 drop-away. By looking at Fig. 1 of the drawings it will readily appear that the car-carrying apparatus is constructed on the closed circuit principle, for if either of the circuits just traced should become open the 25 device EPV is de-energized and an automatic restriction in the movement of the train occurs.

Operation of Fig. 2.—As heretofore mentioned the track element may be in its active 30 or its inactive condition depending on traffic conditions ahead. Bearing this in mind, let us assume that a train equipped with the apparatus shown in Fig. 2 in its normal condition is moving along the track at a 35 comparatively high speed and passes by a track element T having its coil 11 open-circuited. As the car element L passes onto the track element T a sudden increase of flux through the secondary coil S takes place. This increase of flux, it is believed, is mainly 40 due to a diversion of flux from leakage paths around the primary coil P, and possibly to a certain extent due to the increase of the total flux passing through the coil P. In any event, a sudden increase of flux in 45 the secondary coil S takes place which induces a voltage in the control relay CR which is in a direction to impose the voltage impressed upon this secondary circuit by the battery heretofore mentioned. The induction 50 of this voltage in the secondary circuit CR is sufficient to cause this relay to assume its retracted position, thereby opening its front contact 39 and permanently interrupting the secondary circuit. As the car 55 element recedes from the track element T a voltage is induced in the opposite direction in the secondary coil S due to a decrease in flux, this voltage, however, producing no effects because the secondary circuit is already open.

With the control relay CR de-energized, front contact 29 of this relay interrupts the 60 energizing circuit for the device EPV, which restricts the movement of the train

in one of the various ways heretofore mentioned. Proceeding on the assumption that the device EPV is a brake control device, the train is presumed to be brought to a stop and before the train can proceed the engineer is required to depress the push button 70 32 which is only accessible from the ground. Depressing this push button 32 completes a pick-up circuit for the control relay CR which includes the front contact 44 of the 75 push button 32, which circuit is obvious from the drawings. With the control relay CR once picked up it will again stick up through the stick circuit heretofore traced. It should be noted that the reset push 80 button 32 is protected against misuse or abuse by having a normally closed contact 31 contained in the energizing circuit of the device EPV which is open so long as the push button 32 is in its depressed position, 85 this to prevent the engineer from defeating the purpose of the system illustrated by permanently typing down or otherwise maintaining the push button in its depressed position and thereby making the control relay non-stick. 90

Let us now assume that the car element L passes onto a track element T having its coil 11 closed in a circuit of low resistance; that is, when in its inactive condition. Under this condition insufficient voltage is induced in the secondary coil S to de-energize the control relay CR. This, it is believed, is due to the bucking action of the coil 11 which is now closed in a circuit of 100 preferably low resistance. To explain, as the car element L passes onto the track element T a small amount of flux links the core 9 of the track element thereby inducing a comparatively heavy current in the coil 11, which current is in a direction to oppose the flux producing it, so that only a slight increase of flux through the track element T takes place, and consequently the reluctance of the car element L is not materially 105 changed and very little increase of flux in the secondary coil S takes place, so that the control relay CR is not de-energized when a trackway element in its inactive condition 110 is passed over.

From the foregoing it will, of course, be observed that the greater the magneto-motive-force in the primary coil P the less the speed of the train needs to be to effect a certain increase of flux in the secondary coil S. When the speed of the train is less than, say 3 miles per hour, the contact arm 23 moves over the rheostat 34 and thereby increases the current in the primary coil P as the speed decreases from this value. This increase in the primary coil causes the car-carrying apparatus to become more sensitive, so to speak, as the speed is decreased below 3 miles per hour; so that the system, the functioning of which depends upon move- 125 130

ment of the train, becomes more sensitive near zero speed whereby it may be relied on for the transmission of a control influence down to extremely low train speeds. It is, of course, understood that the car-carried system should not be adjusted to its most sensitive adjustment at higher train speeds, because a certain influence is transmitted by track elements when in their inactive condition as well as by crossing rails, and the like.

Description of Fig. 3.—The car-carried apparatus shown in Fig. 3 of the drawings is exactly the same as that shown in Fig. 2 except that a variable potential is applied to the secondary circuit instead of a variable current in the primary circuit. In other words, the pick-up and stick circuits for the control relay CR have been modified by illustrating a battery V having end cells W, X and Y whereby this secondary circuit may be energized by the potential of the battery V plus the potential of one or more of the end cells W, X and Y depending on the speed at which the train is moving at the time. This is accomplished by segments 50, 51, 52 and 53 which are adapted to be engaged by the arm 23 of the governor G, and which are connected to junction points between the battery and end cells by lead wires including resistances 54, 55, 56 and 57. These resistances are used so that as the arm 23 moves from one segment to the other and for a time contacts with both of these segments the particular end cell between these segments will not be short-circuited except through two of these resistances in series.

It is considered unnecessary to describe the operation of the system shown in Fig. 3 since the operation in itself is the same as that of Fig. 2 except that the control relay CR is energized by smaller currents as the speed of the train decreases, whereas in the arrangement shown in Fig. 2 the primary coil P was energized by heavier currents as the speed of the train decreased, the net result in both systems being the same, that is, each system is adjusted more sensitively as the speed of the train decreases, which is desirable for reasons heretofore given.

Description of Fig. 4.—In the arrangement shown in Fig. 4 the current in the primary coil P is not only increased when the speed of the train falls below a certain value, as in the system shown in Fig. 2, but the current in the primary coil P is also intermittently varied so that a pulsating current flows in this coil when the speed of the train is less than that value. The particular arrangement shown in Fig. 4 is identical to that shown in Fig. 2 except that two resistance units 60 and 61 are used in place of the rheostat 34, the resistance unit 60 being cut in the primary circuit for all speeds above, say 3 miles per hour, whereas the resistance unit 61 is cut in the primary

circuit for all speeds less than 3 miles per hour, the resistance 61 being intermittently shunted by the segment 62 contained on the insulated collar 63 of the speed responsive device G.

Operation of Fig. 4.—The operation of the system in Fig. 4 at speeds above 3 miles per hour under danger traffic conditions and for all speeds under clear traffic conditions is the same as that shown in Fig. 2, so that the operation of the arrangement shown in Fig. 4 at speeds of less than 3 miles per hour need only be considered.

Let us assume that a train equipped with the apparatus shown in Fig. 4 moves along the track at a speed of less than 3 miles per hour. As the car element L passes onto the track element T under the assumed conditions only a very low rate of change of flux through the secondary coil S takes place, this rate of change by itself being insufficient to drop the control relay CR. The parts are so proportioned that sometime during the presence of the car element L over the track element T the segment 62 of the governor G completes a shunt around the resistance 61 so that a sudden increase in the primary current takes place regardless of whether the train is moving at the lowest possible speed or whether it is moving from two to three miles per hour, the shunting of the resistance 61 by the segment 62 having of course no effect on the system if the speed is higher than 3 miles per hour, because the resistance 60 is substituted for the resistance 61 in the circuit of the primary coil P by the selecting contact 23 of the speed governor G at speeds above, say, 3 miles per hour. This increase of primary current causes a sudden increase in the flux of the secondary coil S which by reason of the active track element induces a potential in this coil sufficient to drop the control relay CR, and with the control relay CR de-energized the progress of the train is restricted in a manner similar to that shown in the system in Fig. 2. Similarly, the control relay CR may be restored by depressing the push button 32 in a manner as heretofore described. For reasons heretofore given the apparatus shown in Fig. 4 does not transmit a control influence upon passage of the car-carried apparatus over an inactive short-circuited track element.

Description and operation of Fig. 5.—The apparatus shown in Fig. 5 of the drawings is exactly the same as that shown in Fig. 4, except that the governor G, the circuit controlling means governed thereby, the resistances 60 and 61 and the interrupter 62 for intermittently short-circuiting the resistance 61 have been omitted, and in place of this apparatus a resistance unit 70 has been inserted in the energizing circuit for the primary coil P which resistance unit 70 has

connected in multiple therewith an interrupter comprising an insulating drum 71 rotated with the axle of the vehicle and preferably mounted directly thereon having 5 conducting segments 72 contained thereon which are adapted to bridge suitable contact brushes designated by arrows 73 during movement of the train along the track.

In the arrangement shown in Fig. 4, the 10 value of the primary current is intermittently changed only when the speed of the train is less than a certain value assumed to be about 3 miles per hour. This is done, because the primary current is preferably 15 maintained constant and unvarying for speeds above this value, so that the impulse transmitted to the secondary coil S is wholly due to movement of the train at these speeds and increases in magnitude with the speed 20 of the train, so that the control relay CR may be effectively dropped at very high speeds as well as at speeds as low as 3 miles per hour. The arrangement shown in Fig. 5 is proposed to function very much like the 25 system shown in Fig. 4 in spite of the fact that the governor G which has been provided in Fig. 4 to make the current pulsating apparatus ineffective above 3 miles per hour has been omitted.

The apparatus shown in Fig. 5 is designed 30 so as to cause the current in the primary coil P to be practically a constant current, that is a current with practically no ripples superimposed thereon, for speed values higher 35 than say 15 or 20 miles per hour, whereas for speeds below say 3 miles per hour a very pronounced pulsation or ripple is present. This operation of the apparatus shown in 40 Fig. 5 has been substantiated by laboratory tests, and functions on the theory, it is believed, that by reason of the comparatively 45 high inductive reactance in the primary circuit, which includes both the primary coil P and the winding of the train control device EPV, both of which are highly reactive, and the current in this circuit changes only a very small amount during the time that the resistance 70 is not shunted by the interrupter 71-73 for speeds say above 20 miles 50 per hour; whereas for speeds of less than 3 miles per hour the time during which the resistance 70 is shunted is long enough to change the current to its ultimate value. In other words, if there are say 10 units of current 55 flowing in the primary circuit when the resistance 70 is shunted and there are only 4 units of current flowing when the resistance 70 is not shunted, then the current will reach a substantially constant value 60 somewhere between 4 and 10 units when the train is running at comparatively high speeds, this average value depending somewhat on the ratio of the time during which it is shunted and is not shunted. Also, if the 65 speed of the train is very low the current is

fluctuated from a minimum of 4 units to a maximum of 10 units during progress of the train along the trackway. The rate of change of this current is of course substantially the same because the rate of change 70 depends on the constants of the circuit, this because the making or breaking of the circuit as the case may be, of the shunt around the resistance unit 70 is abrupt. In this connection it would at first hand appear that since 75 this rate of change of current is substantially the same whether the speed is low or high that the induction of current in the secondary coil S and in the control relay CR due to this making or breaking of the shunt 80 around resistance 70 when over a trackway device would effect de-energization of the control relay CR, in each case. This is however an erroneous conclusion, because the decrease of current flowing in the control relay CR in itself does not alone determine 85 whether this relay is to assume its de-energized position, but the time during which the current remains reduced is also a factor in determining its de-energization, this because a certain amount of mechanical lag, or time required for the armature to open the stick contact 39, exists; further although the voltage induced in the secondary coil may be 90 high the actual change of current in this coil and the control relay CR may be small due to the impedance of the secondary circuit. In other words, when the train is moving at relatively high speed the fluctuation of the primary current is less in magnitude 95 but varies at substantially the same rate while changing, and probably the voltage induced in the circuit of the control relay CR due to this change is appreciable at 100 these high speeds, but the time during which the current in the control relay CR remains 105 reduced is not sufficiently long to allow this relay to assume its de-energized position, for reasons already given and it is only when 110 there is a rate of change in current flow in the primary coil P which extends over a considerable period of time, as would occur if the train runs at less than say three miles per hour, that the control relay CR is de-energized by reason of such change in current in the primary coil P; and the control relay CR is de-energized when conditions 115 require at the higher speeds, not by reason of the rate of change of current in the primary coil P but by reason of the rate of movement of the car-carried element by the trackway element. Another way of stating 120 the theory upon which this apparatus is believed to function, is that the inertia of the armature of the control relay CR and the 125 distance this armature must move before the stick contact 39 opens, determines the speed of the train below which the control relay CR may be de-energized as a result of the 130 fluctuations of the primary current.

The net result, therefore, is that the apparatus in Fig. 5 functions very much like that illustrated in Fig. 4 as far as the transmission of a control influence to the control relay CR is concerned, but the fluctuations in the primary current are damped out, so to speak, at the higher train speeds, whereas in the arrangement shown in Fig. 4 this primary current is not pulsated at all at the higher speeds. Since the effect as far as transmission of control influences to the control relay CR is concerned, is substantially the same in Fig. 5 as it is in Fig. 4, a detailed description of the operation of Fig. 5 is deemed unnecessary. It may however be repeated at this time, that the functioning of the system shown in Fig. 5 is the same as that shown in Fig. 4 for speeds below say 3 miles per hour; whereas above say 15 miles per hour there is only a small ripple produced on the current flowing in the primary coil P, of the apparatus in Fig. 5, this by reason of the high inductive reactance of this circuit for the frequency of interruption of the shunt around the resistance 70 at such high train speeds. It might be pointed out that the arrangement shown in Fig. 5 is advantageous, in that it does not require a mechanical transmission from the wheels 30 of the vehicle to the car-carried mechanism.

Having thus shown several specific embodiments of the present invention, and having rather specifically described their construction; it is desired to be understood that the particular arrangements illustrated have not been shown for the purpose of signifying the scope of the invention nor indicating the particular apparatus preferably employed in practicing the invention, but have been shown to illustrate the nature of the invention and facilitate its description, and that various changes, modifications and additions may be made to adapt the invention to the particular train control system in connection with which it is to be used without departing from the scope of the invention or the idea of means underlying the same.

What is desired to be secured by Letters 50 Patent is:—

1. Inductive influence communicating means for automatic train control systems comprising; car-carried apparatus including a normally energized flux producing coil; a secondary influence receiving coil; a control relay having a front contact; a secondary circuit including said secondary coil, the winding of said relay, a source of direct current and the front contact of said relay in series; trackway means for inductively coupling said coils; and means for varying the sensitiveness of said car-carried apparatus at different speeds including a speed responsive device.

2. Inductive influence communicating

means for control systems comprising; car-carried apparatus including a normally energized flux producing coil; a secondary influence receiving coil; a control relay having a front contact; a secondary circuit including said secondary coil, the winding of said relay, a source of direct current and the front contact of said relay in series, trackway means for inductively coupling said coils, and means for changing the degree of excitation of said primary coil in accordance with the speed of the train.

3. Inductive influence communicating means for automatic train control system comprising; car-carried apparatus including a normally energized flux producing coil; a secondary influence receiving coil; a control relay having a front contact; a secondary circuit including said secondary coil, the winding of said relay, a source of direct current and the front contact of said relay in series; trackway means for inductively coupling said coils; and means for intermittently changing the energization of said primary coil.

4. Inductive influence means for communicating impulses from the trackway to the vehicle inductively for automatic train control systems comprising; a car-carried apparatus including a normally energized flux producing coil; a secondary influence receiving coil; a control relay having a front contact; a secondary circuit including said secondary coil, the winding of said relay, a source of direct current and the front contact of said relay in series; trackway means for inductively coupling said coils; and means for intermittently changing the energization of said primary coil at speeds below a predetermined speed only.

5. In an automatic train control system; the combination of car-carried means including a core of magnetic material having a primary flux producing coil and a secondary influence receiving coil thereon; a control relay; a primary circuit including a source of direct current potential; a secondary circuit including said secondary coil, the winding and a front contact of said relay, and a source of direct current in series; means for varying the sensitiveness of said car-carried apparatus at different speeds including a speed-responsive device; and of trackway means for inductively coupling said primary and said secondary coil.

6. In an automatic train control system; the combination of a car-carried means including a core of magnetic material having a primary flux producing coil and a secondary influence receiving coil thereon; a control relay; a primary circuit including a source of direct current potential; a secondary circuit including said secondary coil, the winding and a front contact of said relay, and a source of direct current in series;

means for intermittently changing the degree of energization of said primary coil at speeds below a certain speed only; and of trackway means for inductively influencing

5 said primary and said secondary coil.

7. Influence communicating means for automatic train control systems of the intermittent inductive type comprising, a car-

10 carried uni-directional source of magneto-

motive-force, means for pulsating said mag-

neto-motive-force, an influence receiving

15 coil, and traffic controlled trackway means

for causing the induction of a voltage in

said receiving coil in response to said mag-

neto-motive-force.

8. Influence communicating means for automatic train control systems of the intermittent inductive type comprising a car-

20 carried core having a primary and a sec-

ondary coil thereon, a stick relay, a circuit

25 including in series said stick relay a source

of energy and said secondary coil, a uni-

directional source of potential for energizing

20 said primary coil, means for intermit-

tently varying the flow of current due to said

source in said primary coil and trackway

means active under predetermined traffic

conditions ahead for inducing a potential in

said secondary coil to de-energize said relay

in response to the pulsating magnetic field 30

emitted by said primary coil.

9. Inductive influence communicating

means for automatic train control systems

comprising; car-carried apparatus including

a normally energized flux producing coil; 35

a secondary influence receiving coil; a con-

trol relay having a front contact; a second-

ary circuit including in series said secondary

coil, the winding of said relay a source of

40 direct current and the front contact of said

relay; trackway means for inductively cou-

pling said coil; and means for varying the

sensitivity of said car-carried apparatus at

different speeds and for intermittently vary-

ing the flow of current in said flux produc-

ing coil including a speed responsive device.

45 In testimony whereof I affix my signature.

CHARLES S. BUSHNELL.
